UNITED STATES PATENT OFFICE.

JOHN J. CLUIN, OF LOWELL, MASSACHUSETTS.

DESIGN FOR A BADGE.

SPECIFICATION forming part of Design No. 25,556, dated June 2, 1896.

Application filed February 24, 1896. Serial No. 580,584. Term of patent 7 years.

To all whom it may concern:

Be it known that I, JOHN J. CLUIN, a citizen of the United States, residing at Lowell, in the county of Middlesex and Commonwealth 5 of Massachusetts, have invented a new and original Design for a Badge, of which the following is a specification, said design being represented in the accompanying drawing.

The leading feature of my design consists 10 in a horseshoe arranged vertically with the toe or closed end upward and surmounted by an eagle standing with spreading wings grasping arrows, a stag's head upon a background framed within the horseshoe and provided 15 with antlers which extend in front of said horseshoe at the sides and near the top of the same, two United States' flags borne on staffs crossed behind the horseshoe on opposite sides of the eagle, two ears of grain arranged 20 at the sides of said horseshoe and inclining outwardly therefrom in front of the striped portions of said flags and a scroll concealing the lower ends of said ears and the lower end of said horseshoe.

The accompanying drawing is a front elevation of the badge, *a* being the horseshoe; *b*, the arrows; *c*, the eagle; *d*, the stag's head with antlers *d'*, which extend in front of the sides of the horseshoe *a*; *e*, the background supporting the stag's head *d*; *f*, the flags hanging from the staffs *g*, the latter being crossed behind the horseshoe and background; *h*, ears of grain; *i*, the scroll arranged in front of and concealing the lower ends of said ears and horseshoe. 25

I claim as my invention—

The design for a badge, substantially as herein shown and described.

In witness whereof I have signed this specification, in the presence of two attesting witnesses, this 19th day of February, 1896. 40

JOHN J. CLUIN.
